TENS TRANSFER MECHANISM

Edward P. Drake, Glendale, Calif., assignor to
 Clary Multiplier Corporation, Los Angeles,
 Calif., a corporation of California

Application March 13, 1945, Serial No. 582,554

9 Claims. (Cl. 235—138)

1

The present invention relates to calculating machines, and has particular reference to machines of the type disclosed in the copending application of Robert E. Boyden, Serial No. 582,553 filed March 13, 1945. Reference may be had to said application for a disclosure of a complete calculating machine in which the embodiment of the present invention may be incorporated. However, it is to be understood that the invention is not limited to a machine of the above type but may be incorporated in any machine or device wherein it is desired to accumulate values.

One object of the present invention is to provide a simple and improved accumulator and tens transfer mechanism which is absolutely reliable at high speeds.

Another object is to provide a two directional accumulator capable of high speed operation.

Another object is to positively prevent overthrow and/or rebound of an accumulator element during a tens transfer operation.

Another object is to provide a tens transfer mechanism in which the conditioning and determination of the direction of a tens transfer operation is effected directly by an accumulator element.

Another object is to reduce the force required to condition a tens transfer device to effect a tens transfer.

The manner in which the above and other objects of the invention are accomplished will be readily understood on reference to the following specification read in conjunction with the accompanying drawings wherein;

Fig. 1 is a transverse sectional view through an accumulator embodying the present invention, with the transfer pawl in a neutral condition, and is taken along the line 1—1 of Fig. 4.

Fig. 2 is a transverse sectional view, similar to that of Fig. 1, but showing the transfer pawl in a "subtract" condition.

Fig. 3 is a transverse-sectional view similar to Figs. 1 and 2, but taken along the line of 3—3 of Fig. 4 and illustrating the transfer pawl at the end of its stroke.

Fig. 4 is a front view of several orders of the accumulator.

Fig. 5 is a longitudinal sectional view through the control section of an adding machine embodying the accumulator of the present invention.

Fig. 6 is a longitudinal sectional view through the adding machine, illustrating the key board and one of the drive racks.

2

Fig. 7 is a side view of the gear train for transmitting rotation to the tens transfer shaft.

The machine in which the preferred embodiment of the invention is illustrated is of the adding machine type and includes a full keyboard comprising a series of rows of amount keys as more fully disclosed in said Boyden application. Each row comprises nine keys ranging in value from 1 to 9, certain of which are illustrated at 9 in Fig. 6.

10 Each key 9, when depressed, serves as a stop to limit the movement of an aligned drive rack 19 which drives the accumulator to enter therein a value corresponding to the value of the depressed aligned key and to set the printing mechanism to print the said value. The racks are guided for longitudinal movement at the rear thereof by a stationary rod 81, embraced by slots 83 formed in the racks, there being a suitable support (not shown) for likewise guiding the forward ends of the racks.

15 Each rack is provided with equally spaced shoulders 79, the spacings of which are slightly larger than the spacings of the keys 9 so that each rack, when yieldably advanced toward the front of the machine will strike the key stem of a depressed key after it has moved forward a number of increments equal to the value of the depressed key. Also formed on each rack 19 is 20 a pair of rack gear sections 83 and 84 located on opposite sides of an associated accumulator gear 85 rotatably mounted on an accumulator shaft 86 forming part of the accumulator unit.

25 A plurality of control keys or bars, some of which are illustrated in Fig. 5, are provided to cause the machine to perform different functions. For example, a subtract bar 13 is provided, which when depressed, causes the machine to subtract an amount set up on the keys 9 from an amount entered in the accumulator which will be described presently. A non-add bar 14 is provided which, when depressed, causes the machine to print a value (in a manner not shown) without entering the same in the accumulator. A subtotal bar 18 is provided to cause the accumulator to be returned to zero value for the purpose of registering the racks and printer at the total value previously accumulated in the accumulator so as to print such value and to then return the 30 accumulator to its previous accumulated value. A total bar 17 is provided to return the accumulator to zero so as to register the racks and printer at the accumulated value. In this case the accumulator is allowed to remain in its zero position after the printing operation.

The accumulator is of the two directional subsequent transfer type capable of receiving both additions and subtractions.

Referring to Figs. 1 to 4, inclusive, the accumulator shown therein is arranged to be raised or lowered for the purpose of engaging the various accumulator gears 85 with either the upper rack gear sections 83 or the lower rack gear sections 84 (Fig. 6) of the racks 19 in accordance with the type of problem to be performed. During an additive operation, the accumulator is raised to mesh the gears 85 with the upper rack gear sections 83 whereby the gears will be rotated in a counter-clockwise direction during the subsequent forward movements of the racks 19, while, during a subtractive operation, the accumulator is lowered to mesh the gears 85 with the lower rack gear sections 84 so that the subsequent forward rack movement will drive the gears in a clockwise direction.

The accumulator comprises in general the hereinbefore mentioned accumulator shaft 86 and a second shaft 87, both rotatably mounted in bearings formed in a series of ordinarily spaced brace plates 10 (see Fig. 4 in particular) rigidly held in spaced relation with each other by suitable interlocking combs 11 well known in the art. A rod 12 is passed through the various plates 10 adjacent each comb to hold the latter in locking position.

The shafts 86 and 87 are guided for vertical movement in vertically extending slots, one which is shown at 13, (Fig. 5) formed in side plates 13a of the machine and thus carry the various brace plates 10 and tens transfer mechanism comprising the accumulator unit.

For the purpose of raising and lowering the accumulator unit in accordance with the type of problem being performed, there is provided a box cam 94 (Fig. 5) pivoted on a stationary frame stud 95 and having a cam groove 96 therein embracing a roller 97 rotatably mounted on the shaft 86 at the left hand end thereof. Clockwise rocking movement of the cam 94 beyond its central illustrated position will raise the accumulator into its adding position while counter-clockwise rocking of the cam will lower the accumulator into its subtractive position. Suitable means, such as a shaft 99 rotatably mounted in the side frames of the machine and having arms (not shown) attached at opposite ends thereof and embracing the shaft 86 as illustrated in said Boyden application are preferably provided to insure parallel movement of the accumulator in its vertical travel.

The above noted meshing operation is performed in addition and subtraction operations in advance of each forward stroke of the racks 19 so that, as the racks 19 are driven forward, the gears 85 will be rotated a number of increments determined by the extent of travel of the corresponding racks, and since there are ten teeth in each gear, each tooth advance of the gear will represent one digit entered into the particular order of the accumulator in which said gear is located. At the end of the forward travel of the racks in addition, subtraction and totaling operations the gears 85 will be demeshed from the gear rack sections and located in their neutral positions illustrated in Fig. 6 to permit the return of the racks without affecting the accumulator.

As each gear 85 moves through one revolution or ten tooth spaces as a result of accumulating ten digits it conditions a transfer mechanism to subsequently enter one digit into the gear 85 of the

next arithmetically higher order to the left. For this purpose, a transfer pawl 15 is provided, being capable of rotating its associated gear an increment of one tooth space in either direction.

5 Each pawl 15 surrounds its associated gear 85 and is pivoted on one side of the gear 85 at 115a on a cam follower lever 16 pivotally supported on the lower shaft 87. Lever 16 is provided with a roller 16a adapted to be engaged and moved by 10 an aligned one of a series of transfer cams 18 to be described in detail hereinafter.

Pawl 15 is provided with three detents 17, the central one of which is normally engaged by the roller 119a of a centralizer lever 119 pivoted on 15 a brace plate stud 20 attached to the associated brace plate 10 and pressed against the pawl by a spring 21 extending between the centralizer and a stud 22, also attached to the brace plate 10. In addition to holding the pawl 15 in any of three 20 positions, the centralizer 119 also normally maintains the pawl in a rearward position as illustrated in Figs. 1 and 2 wherein the lever 16 rests against the adjacent comb retaining rod 12, and is capable of returning the pawl from its forward position illustrated in Fig. 3 after the associated cam 18 is removed from contact with the roller of the associated lever 16.

Each gear 85, as it rotates in a clockwise direction from its "zero" position illustrated in Fig.

30 1 to its "9" position illustrated in Fig. 2 during a subtraction operation, carries a tooth 23 attached integrally thereto into engagement with an ear 24 located on the pawl 15 on the side of the gear 85 opposite the side thereof at which the pivot 115a is located. The tooth 23 thus rocks the pawl 15 upwardly about its pivotal support 115a. Substantially halfway through its upward movement, the roller 119a on the centralizer 119 moves over the tip 25 on the transfer pawl located between the central and lower detents 17. The spring 21 thus becomes effective to cause the centralizer to tend to exert a camming force on the pawl so as to move it further into its fully conditioned position illustrated in Fig. 2. However, at 45 normal speeds the tooth 23 supersedes such force and maintains contact with the ear 24 until such tooth reaches substantially its position illustrated in Fig. 2. From there on, the momentum of the pawl and the camming effect of the centralizer 50 carry it to its fully conditioned position. In view of the longer radius of the arc of travel of the ear 24 the latter will gradually move outward relative to the tooth 23 so that as it reaches its fully conditioned position it will be entirely clear of the 55 tooth, permitting the latter to continue its rotational movement without interference with the tooth. In view of this construction wherein the tooth 23 exerts a force on the pawl 15 throughout its total rotative travel between nine and zero 60 registration it will be seen that such required force may be reduced to a minimum and the shock and strain upon the various parts of the accumulator likewise reduced. In the fully conditioned position of the pawl 15, a transfer tooth 15a thereon is located directly behind a tooth 26 of the gear 85 so that in a subsequent transfer phase 65 of the operation in which the cam follower arms 16 are rocked by the cams 18 to advance the pawls 15, the tooth 15a will engage and drive the gear 85 one tooth space in a clockwise or subtractive direction.

Likewise, during an additive operation and when an accumulator gear 85 rotates counter-clockwise from a "9" position to a "0" position 75 the tooth 23 thereof will strike the ear 24 of the

associated transfer pawl 15, moving the latter into a lower position (not shown) in which the roller 119a of the associated centralizer 119 engages the upper detent 11. Since the pawl 15 is symmetrical exactly the same action will occur as in a subtractive conditioning operation except that the gear 85 will be rotated one tooth in a counter-clockwise or additive direction. That is, as the pawl 15 is lowered a tooth 28 thereon, will be located opposite a tooth on the gear so that when the pawl is subsequently moved forward the tooth 28 will advance the gear one tooth space.

It will be noted that during additive, subtractive and totaling operations the accumulator will be disengaged from the racks, i. e. it will be returned to its neutral position as shown in Fig. 6, prior to the transfer phase which occurs late in the machine cycle. Therefore, at the end of the digitizing phase of the cycle the pawls 15 in all the orders which are to receive a tens transfer will be conditioned or located in an upper or lower position depending on the type of operation, and the gears will be completely demeshed from the racks.

Means are provided for effecting the tens transfer in the various orders of the machine beginning at the next to the lowermost or right hand order when viewing the accumulator from the front, as in Fig. 4. For this purpose, a transfer shaft 30 is rotatably mounted in the side plates of the machine in a manner not shown and has mounted thereon the various transfer cams 18. The cams 18 are held in spaced relation with each other by sleeves 30a. It will be noted on reference to Figs. 1 and 2 that the various cams 18 are arranged in a helical row about the shaft 30 and for the purpose of facilitating assembly and manufacture of the various transfer cams 18, and to enable interchangeability of the cams, they are all made identical with symmetrical contours and each is provided with an octagonal opening adapted to be fitted over the square section of the shaft 30. Also, a line through two diametrically opposed points in the opening of each cam lying adjacent the axis of symmetry extends 22½ degrees from said axis so that by appropriately fitting the cams over the shaft they may be arranged at 22½ degrees from each other.

It will be noted that the centralizers 119 and the levers 16 form substantially parallel link arrangements to carry the pawls 15 through paths which closely approximate a straight line regardless of the angular condition of the position of the pawl about its pivot 115a. During an idle transfer stroke, i. e. when a pawl is not conditioned for a transfer, the latter will travel through its stroke without engaging the gear 85 but during a transfer stroke in which the pawl has been conditioned to cause a transfer one or the other of the teeth 15a and 28 of the pawl will drive said gear. During such driving movement, whichever tooth is driving the gear 85 will be engaged by a succeeding tooth of the gear 85 and will be gradually shifted thereby into its neutral position so that regardless of whether a subtractive or additive transfer is being made the pawl will always come to rest in its neutral position illustrated in Fig. 3. For example, during a subtractive transfer operation, and as the tooth 15a of pawl 15 drives the gear tooth 26, the succeeding gear tooth 31 will cam the tooth 25 downwardly, into its neutral position. This camming action will be completed just as the

gear tooth 26 reaches its new position. It will also be noted that the pawl teeth 15a and 28 are so spaced that as the tooth 31 cams the pawl downward toward its neutral position, the upper tooth 28 follows a gear tooth 32 and locates behind the succeeding tooth 33 thereby positively preventing overthrow of the gear. Furthermore, rebound of the gear from its advanced position will also be prevented since at the end of the stroke of the pawl both teeth 15a and 28 will be located behind the adjacent gear teeth 26 and 33, respectively, as shown in Fig. 3.

A yieldable centralizer pawl 320 is provided to hold each gear in any registered position. As shown in Figs. 3 and 4, the pawl 320 is pivoted on the brace stud 20 in juxtaposition with the associated centralizer 119 and is held in engagement with the gear teeth by a spring 32a tensioned between the pawl and the stud 22.

Means are provided for rotating the transfer shaft 30 during the latter part of the machine cycle and after the digitizing phase has been completed. As illustrated in Fig. 7 a mutilated gear 126 and a disc 127 are keyed in juxtaposition with each other on a cyclically operable shaft 51 forming the main driving shaft of the machine. The disc 127 has a depression 128 formed in the edge thereon in alignment with the teeth of the gear 126. The gear 126 is adapted to mesh with a wide pinion 129 rotatably mounted on a frame stud 130 and having its width extending across both the gear 126 and the disc 127. The portion of the pinion 129 in alignment with the gear 126 is fully toothed, while the portion thereof which is in alignment with the disc 127 has a pair of adjacent teeth cut away to form a bearing surface 131 against which the periphery of the disc 127 normally rides, whereby to prevent rotation of the pinion whenever the teeth of the gear 126 are out of mesh with the teeth of the pinion. Therefore, at approximately ⅓ of the revolution of the shaft 51 in the direction of arrow A, the disc will merely ride against the bearing surface 131 of the pinion until the teeth of the gear 126 mesh with the full toothed portion of the pinion 129 at which time the depression 128 will be aligned with the pinion teeth, permitting rotation of the latter. Pinion 129 is arranged to drive the transfer shaft 30 through an idler 132 journaled on a frame stud 133 and meshing with a pinion 134 fixed to the shaft 30. The length of the toothed portion of gear 126 is such that the shaft 30 will be rotated one complete revolution, and will come to rest in its normal position shown in Figs. 1 and 2.

It will be noted that the shaft 30 is rotated in a clockwise direction so that the transfer cam 18 located in the units or left-hand order (as viewed in Fig. 4) will be the first to effect the transfer stroke of its associated transfer pawl 15. The cams 18 are so spaced angularly that any one cam will effect a transfer stroke of its associated transfer pawl before the next adjacent higher order cam will cause its transfer pawl to move.

As described hereinbefore, various control bars, including bars 13, 14, 17 and 18 (Fig. 5) are provided for controlling and effecting operation in the machine, depression of each of these bars 70 causing rotation of the shaft 51 one complete revolution as more fully disclosed in the aforesaid Boyden application.

The above control bars also cause raising and lowering of the accumulator to mesh the gears 85 with either the upper rack gear section 83

(Fig. 6) or the lower rack gear section 84 of the rack 19, depending upon the type of operation to be performed. For this purpose mechanism is provided which is under control of the different control bars for determining and effecting the positioning of the accumulator.

The hereinbefore mentioned box cam 94 (Fig. 5) carries a pair of pins 257 and 258 arranged on the opposite sides of the pivot 95. These pins are adapted to be selectively engaged by a hook member 259 pivoted to a three armed cam follower 260 which is pivoted on the rod 81. The cam follower 260 is urged counter-clockwise by a spring 261 connected between one arm of the cam follower and a frame pin 262 to press a roller 263 on another arm thereof against a cam 264 keyed on the cyclic drive shaft 51. Cam 264 has a high portion extending over substantially one half of its periphery whereby to rock the cam follower 260 and thereby drive and hold the hook member 259 rearward during approximately the first half of a machine cycle. Normally, during additive operations or when the machine is at rest, the hook member 259 is raised by a tension spring 265 whereby a slot 266 therein embraces the upper pin 257 so that upon rotation of the shaft 51 under control of an "add" bar or other control bar (not shown) the hook is moved rearward and it will rock the cam 94 clockwise to raise the accumulator into its additive position.

For the purpose of locating the hook 259 in a lowermost or intermediate position, a control bar 267 is provided, being supported for longitudinal movement by a pair of parallel links 268 pivotally suspended from the frame by pins 269. The bar 267 has four camming surfaces 270 thereon underlying pins 232 carried by links 233 pivoted on frame pins 234. Pins 232 underlie the stems of the control bars 13, 14, 17 and 18 and are urged upwardly by springs 235 extending between the pins and frame studs 236 to normally hold the control bars in raised positions.

The bar 267 is connected by a pin and slot connection 271 to a bellcrank 272 pivoted on a frame stud 273 and having a pin 274 at the opposite ends thereof embraced by a slot 274a formed in the hook 259.

The camming surfaces 270 of the bar 267 are so arranged that upon depression of the "minus" bar 13, the "total" bar 18 or the "sub-total" bar 17, the control bar 267 will be moved forwardly its fullest extent which, through the bellcrank 272 will lower the hook member 259 to cause a slot 275 therein to embrace the pin 258 on cam 94 so that subsequent rearward movement of the hook member 259 will place the accumulator in its lower subtractive position. The contour of the camming surface 270 underlying the "non-add" bar 14 is such that depression of this bar will move the bar 267 and hook member 259 into their neutral positions wherein both slots 266 and 275 of the hook member 259 will be out of registry with the pins 257 and 258 of the cam 94. Consequently, during the subsequent rearward movement of the hook members 259 the cam 94 will remain in its neutral position as illustrated in Fig. 5 and, therefore, the accumulator will not be actuated during the subsequent forward movement of the racks 19.

In order to normally maintain the cam 94 in its neutral position when it is so placed, a centralizer 276 is provided, being pivoted on a frame stud 277 and urged in a clockwise direction by a tensioned spring 278 so as to force a roller 279 carried thereby into a depression formed on

the lower periphery of the box cam 94. The remainder of the lower periphery of the box cam is arranged concentric about the frame stud 95 so that the centralizer roller will effect only a frictional force against the cam as it is moved on either side of its neutral position.

In totaling operations, the accumulator is returned in a subtractive direction to zero during the first part of the operating cycle and is then placed in its neutral position in the same manner as in addition and subtraction operations, while in sub-totaling operations, the accumulator is first returned to zero during the first part of the cycle and is then again reset at its former accumulative value during the latter half of the cycle. Therefore, it is necessary in the latter operation to maintain the accumulator in mesh with the drive racks 19 until the latter have returned to their rearward positions illustrated in Fig. 6. To this end, a second cam 1279 is mounted on the shaft 51 in juxtaposition with the cam 264 and is provided with a high portion extending around the major portion of the periphery thereof. The cam engages a roller 280, normally aligned with the roller 263, and carried by a second cam follower 281 also pivoted on the rod 81 and urged counter-clockwise by a spring 281a. A slot 282 is formed in the rearwardly extending arm of the bellcrank 281, which slot is coextensive with the slot 283 formed in cam follower 260. However, it will be noted that the rearwardly extending arm of the bellcrank 281 is somewhat shorter than the similar extension of the cam follower 260.

A pin 284 carried by a link 285 slides within one or both of the slots 282 and 283 depending on its position longitudinally of the machine. The link 285 is connected at its forward end to the lower arm of the bellcrank 233a which is associated with the sub-total bar 18 and is so arranged that when the bar 18 is in a raised position as indicated in Fig. 5 the pin 284 will be located solely within the slot 283 of the cam follower 260. However, upon depression of the bar 18 the pin 284 will be moved forwardly to locate within both the slots 282 and 283. In this condition, i. e. during a sub-totaling operation, the two members 260 and 281 will move as a unit and the cam 1279 will therefore, through the hook 259 hold the accumulator engaged with the drive racks 19 throughout the major portion of the cycle.

Referring to Figs. 1 to 4, a series of ordinarily spaced zero stop levers 50 are keyed to the shaft 87 adjacent the various gears 85 and are, during totaling and sub-totaling operations, rocked counter-clockwise by the shaft 87 into blocking positions relative to ears 51 formed integral with the accumulator gears 85. Thus, when the gears 85 are rotated subtractively in a clockwise direction by the drive racks 19 they will return to zero positions indicated in Fig. 1 at which time the zero locating ear 51 of each gear will be blocked by a lug 50a of its associated zero stop lever 50, thereby also stopping its associated rack 19.

The shaft 87 and zero stop levers 50 are rocked counter-clockwise by power under control of the total bar 17 and sub-total bar 18 and in order to accomplish this an arm 288 (Fig. 5) is keyed to the shaft 87 and has a pin 289 thereon embraced by a slot 289a in a floating lever 290 which normally rides on the stationary frame pin 277. The forward end of lever 290 is pivoted to the lower end of a link 292, the upper end of which is pivotally connected to a cross link 293 intermediate its ends. The link 293 is pivotally connected at

the opposite ends thereof to the pins 232 underlying the stems of the control bars 17 and 18.

Upon depression of either of these two control bars the link 292 will be lowered sufficiently to rock the lever 290 counter-clockwise about the stationary pin 277 to position a hook 294 thereon in the path of a pin 295 carried by the cam follower 281 so that as the latter is rocked counter-clockwise at the beginning of total or sub-total operations as explained herein above, the pin 295 will force the lever 290 forwardly, rocking the lever 288 and shaft 87 counter-clockwise against the action of a tension spring 301 attached to the lever so as to carry all of the zero stop levers 50 into blocking position relative to the zero locating ears 51 on the gears 85. Thus, as the machine continues its cycle, the racks 19 will be driven forward, rotating the gears 85 in a subtractive direction until they are stopped in their zero positions by the levers 50. The racks will therefore stand in positions mechanically representing the total values previously registered by the accumulator whereby to cause the printing mechanism to register and print this value.

If desired numbered dials may be attached or geared in any suitable manner to the gears 85 so that amounts registered thereby may be visibly indicated.

Having thus described one embodiment of the invention, what I desire to secure by Letters Patent is:

1. In a calculating machine having a plurality of rotatable accumulator elements of different denominational orders and means for driving said elements; tens transfer mechanism comprising the combination of a transfer actuator for each of said elements, said actuator having a driving tooth thereon, means for moving said actuator through a transferring stroke, means for normally guiding said actuator in a path wherein said tooth is ineffective to drive said element during said stroke, means actuated by one of said elements upon movement thereof between nine and zero registration for conditioning the actuator associated with the next higher order element to cause said tooth thereof to drive said next higher order element one increment during said stroke thereof, and a second tooth carried by said last mentioned actuator for engaging said next higher order element to positively prevent overthrow thereof beyond said increment.

2. In a calculating machine having a plurality of rotatable accumulator elements of different denominational orders and means for driving said elements; tens transfer mechanism comprising the combination of a transfer actuator for each of said elements, an element driving tooth on said actuator, means for moving said actuator through a transferring stroke, said actuator being arranged to move selectively in a path wherein said tooth is ineffective to drive said element and in a second path wherein said tooth is effective to drive said element during said stroke, means for guiding said actuator in either of said two paths, means impelled by one of said elements upon movement thereof between nine and zero registration for locating the actuator associated with the next higher order element in said second path whereby to drive the same during said stroke, and a second tooth on each of said actuators adapted to engage its associated element upon movement of its respective actuator through said stroke whereby to prevent overthrow of said associated element.

3. In a calculating machine having a plurality

of rotatable toothed accumulator elements of different denominational orders and means for driving said elements; tens transfer mechanism comprising the combination of a transfer actuator for each of said elements, means for moving said actuator through a transferring stroke, means forming a pivotal connection between said actuator and said moving means, locating means for alternatively maintaining said actuator in one rocked position about said pivotal connection wherein said actuator misses said element during said stroke and for maintaining said actuator in a second rocked position wherein said actuator engages a tooth of said element whereby to drive the same during said stroke, means actuated by the next lower order element on movement thereof between nine and zero registration for moving said last mentioned actuator into said second rocked position, and means comprising a second tooth on said last mentioned element operable during said driving movement of its associated actuator to move the latter into its said first mentioned rocked position.

4. In a calculating machine having a plurality of rotatable accumulator elements of different denominational orders and means for driving said elements; tens transfer mechanism comprising the combination of a transfer actuator for each of said elements, said actuator having two teeth thereon, means for moving said actuator through a transferring stroke, means for normally guiding said actuator in a path wherein said teeth miss said element during said stroke, and means actuated by one of said elements upon movement thereof from nine to zero registration for conditioning the actuator associated with the next higher order element to cause one of said teeth to drive the same one increment in one direction during said stroke, said conditioning means being actuated by said one element upon movement thereof from zero to nine registration for conditioning said last mentioned actuator to cause the other of said teeth to drive said next higher order element one increment in an opposite direction, both of said teeth being operable substantially at the end of said transfer stroke to positively prevent overthrow and rebound of said element beyond said increment.

5. In a calculating machine having a plurality of rotatable accumulator elements of different denominational orders and means for driving said elements; tens transfer mechanism comprising the combination of a transfer actuator for each of said elements, means for moving said actuator through a transferring stroke, means on said actuator forming a pair of driving teeth, means normally guiding said actuator in a path wherein said teeth are ineffective to drive said element during said stroke, and means actuated by one of said elements on movement thereof from nine to zero registration to condition the actuator associated with the next higher order element to cause one of said teeth thereof to drive said higher order element one increment in one direction during said stroke, said last mentioned means being adapted to be actuated by said one element on movement thereof from zero to nine registration to condition the actuator associated with said next higher order element to cause the other of said teeth thereof to drive said next higher order element one increment in the opposite direction during said stroke, said next higher order element being operable during said driving movement of its associated actuator to condition the latter to engage both of said teeth thereof with said last

mentioned element whereby to prevent overthrow thereof beyond said increment.

6. In a calculating machine having a plurality of rotatable accumulator elements of different denominational orders and means for driving said elements; tens transfer mechanism comprising the combination of a transfer actuator for each of said elements, means on said actuator forming a pair of driving teeth, a pair of swinging levers pivotally supporting said actuator and arranged to swing in substantially parallel relationship to guide said actuator through a transferring stroke, means for moving said actuator through said transferring stroke, said levers being normally effective to guide said actuator in a path wherein said teeth are ineffective to drive said element, and means actuated by one of said elements upon movement thereof between nine and zero registration for arranging the pivotal connection between the actuator associated with the next higher order element and one of said supporting levers therefor to guide said last mentioned actuator in a path wherein one of said teeth thereof drives said last mentioned element one increment in one direction during said stroke, said arranging means being adapted to be actuated by said one element upon movement thereof from zero to nine registration to arrange said pivotal connection to guide said last mentioned actuator in a path wherein the other of said teeth thereof drives said last mentioned element one increment in the opposite direction, said last mentioned element being effective during driving movement of said actuator to arrange said pivotal connection to cause said actuator to engage both of said teeth thereof with said last mentioned element whereby to prevent overthrow thereof beyond said increment.

7. In a calculating machine having a plurality of rotatable accumulator elements of different denominational orders and means for driving said elements; tens transfer mechanism comprising the combination of a transfer actuator for each of said elements, means on said actuator forming a pair of driving teeth, a pair of swinging levers pivotally supporting said actuator and arranged to swing in substantially parallel relationship to guide said actuator through a transferring stroke, means for moving said actuator through said transferring stroke, said levers being normally effective to guide said actuator in a path wherein said teeth are ineffective to drive said element, means actuated by one of said elements upon movement thereof between nine and zero registration for arranging the pivotal connection between the actuator associated with the next higher order element and one of said supporting levers therefor to guide said last mentioned actuator in a path wherein one of said teeth thereof drives said higher order element one increment in one direction during said stroke, said arranging means being adapted to be actuated by said one element upon movement thereof from zero to nine registration to arrange said pivotal connection to guide said last mentioned actuator in a path wherein the other of said teeth thereof drives said higher order element one increment in the opposite direction and means for moving said last mentioned actuator into a position wherein both of said teeth thereof engage 70 said higher order element whereby to prevent overthrow of said higher order element beyond said increment.

8. In a calculating machine having a plurality

of accumulator gears of different denominational orders and means for driving said gears; tens transfer mechanism comprising the combination of a transfer actuator for each of said gears, means on said actuator forming a pair of driving teeth for driving said gear, means comprising a swinging lever pivotally connected to said actuator at one side of said gear for reciprocating said actuator through a transferring stroke; means for guiding said actuator through a path wherein said teeth are ineffective to drive said gear during said stroke, said guiding means comprising a second swinging lever movable in substantially parallel relation to said first mentioned lever, and means forming a second pivotal connection between said actuator and said second lever at the opposite side of said gear; and means actuated by one of said gears upon movement thereof from nine to zero registration to arrange the pivotal connection between the actuator associated with the next higher order gear and said second lever associated therewith to guide said last mentioned actuator in a path wherein one of said teeth thereof drives said next higher order gear one increment in an additive direction, said arranging means being adapted to be actuated by said one gear upon movement thereof from zero to nine registration to arrange said last mentioned actuator in a path wherein the other of said teeth thereof drives said next higher order gear one increment in a subtractive direction, said next higher order gear being effective during driving movement of said last mentioned actuator to arrange said last mentioned pivotal connection thereof to cause said last mentioned actuator to engage both of said teeth thereof with said next higher order gear whereby to prevent overthrow thereof beyond said increment.

9. In a calculating machine having a plurality of rotatable accumulator elements of different denominational orders and means for driving said elements; tens transfer mechanism comprising a transfer actuator for each of said elements, means on said actuator forming a pair of driving teeth, means for moving said actuator through a transferring stroke, means for normally retaining said actuator in an ineffective condition during said movement thereof, and means responsive to movement of one of said elements, when a tens transfer is indicated, for rendering the actuator associated with the next higher order element effective to cause one of said teeth to drive said higher order element, means on each of said elements for returning its associated actuator to ineffective condition during said movement thereof while in effective condition, both of said teeth being effective to positively lock the associated element against rebound and overthrow during the last portion of said movement thereof.

EDWARD P. DRAKE.
